[57] CLAIM

The ornamental design for a programmable audio cassette recorder, as shown and described.

DESCRIPTION

FIG. 1 is a perspective view of a programmable audio cassette recorder showing my new design;

FIG. 2 is a front elevational view thereof;

FIG. 3 is a rear elevational view thereof;

FIG. 4 is a top view thereof;

FIG. 5 is a left side elevational view;

FIG. 6 is a right side elevational view; and,

FIG. 7 is a bottom view thereof.

The broken line showing of numbers and letters in FIGS. 1 and 3-5 is for illustrative purposes only and forms no part of the claimed design.
